UNITED STATES PATENT OFFICE.

JAMES F. TRAVIS, OF NEW YORK, N. Y.

DESIGN FOR GAS-BRACKET.

Specification forming part of Design No. 6,809, dated August 19, 1873; application filed August 4, 1873.

To all whom it may concern:

Be it known that I, JAMES F. TRAVIS, of the city of New York, in the county and State of New York, have invented a new and original Design for a Gas-Bracket, which will be fully understood from the following description in connection with the accompanying drawing:

My present design is intended for a wall gas-bracket, which class of brackets are usually affixed to gas openings in the walls of a room, or on columns, balconies, &c., in such manner that but one side of the bracket is presented to view.

A A designate the branches, and B the body of the bracket, to the rear of which body the pipe, which supplies gas to the branches, is connected. The said branches are shown as provided with shut-off cocks or plugs a, and with burners and globe-rings b, in the usual manner. The cut-off cocks are shown as having ornamental keys m, for operating them. C is a pendant extending downward from the lower side of the body, and D is a standard proceeding upward from the upper side of the body, the said pendant and standard forming right angles with the branches A A. The pendant and standard are preferably provided with ornamental ends or heads c d, respectively. To the under side of each branch A, as well as to each side of the pendant C, a strip, E F G, is attached, so as to leave an intervening space by the connections e f g. The portion of the said strip, lettered E, runs parallel with the branches A A, and the portion lettered G runs parallel with the pendant C, and the intervening portion F is

curved to correspond with the curve of the body. The outer ends of the strip are preferably provided with ornamental knobs or heads h i. To the upper side of each branch A, as well as to the standard D, a strip, K L M, is attached, so as to leave an intervening space by connections j k, that portion of said strip lettered K being parallel with the branch A, and that portion lettered M being parallel with the standard D, and the intervening portion L being curved to correspond to the curve of the body, and the outer ends of the said strip being preferably provided with knobs or heads n n. The body B is provided with a medallion, H, representing a head or other suitable figure.

It will be observed that my design, above described, gives to the bracket a very neat and attractive appearance, and that it is not difficult to discern a cross formed by the rectangular parts, while the ornamental strips present a large circle, within which is the body exhibiting a medallion.

What I claim as my invention is—
A design for a gas-bracket, in which the body is provided with a medallion, and the ornamental strips E F G and K L M form a circle around the medallion, and also serve as an ornamentation to the rectangular portions A A, C, and D of the device, substantially as herein shown and described.

JAMES F. TRAVIS.
